2,644,375

COMBINATION LINING AND EDGE
FINISHING MACHINE

Louis Triolo, Brooklyn, N. Y.

Application June 29, 1951, Serial No. 234,373

4 Claims. (Cl. 93—62)

1

This invention relates to container machinery and relates more particularly to a combination lining and edge finishing machine for the making of flat containers.

The machine of the present invention has special usefulness in the making of envelope type containers for phonograph records. With the advent of the long playing record the record "albums" are seldom used since the single records take the place of the plural records and each record is sold in the single envelope. The container includes one wall formed of relatively heavy cardboard and a second wall of paper, three edges of which are glued to the outer surface of the heavier wall, leaving the fourth edge open for the introduction of the record. This latter wall is then covered by a label of the same size as the wall so that the folded-in edges are covered as well. The machine of the present invention has no reference to the label applying operation.

An important object of the present invention is to provide a machine of the character described which accurately folds the aforesaid three edges of the paper blank around the edges of the cardboard wall and then presses such edges, to which adhesive material has previously been applied firmly against the opposite face of the wall so that the adhesive bond is effective and complete.

Another object of the invention is to provide an edge finishing machine which may be operated substantially continuously and wherein the only limitation on its speed of operation is that of speed of the operator who feeds the superimposed blanks to the machine.

A further object of the invention is to provide improved folding members for bending downwardly the upstanding edges of the blank just before they are introduced to the rollers which apply the final pressure.

The application of the second wall to the first wall is essentially a lining operation even though adhesive is applied only to the flaps which are folded, pressed and finished by the machine.

In the drawings:

Fig. 1 is a plan view of the machine embodying the present invention;

Fig. 2 is a central vertical section taken through the machine, the section being taken on line 2—2 of Fig. 1;

Fig. 3 is a broken elevation of the right hand side of the machine;

Fig. 4 is a broken elevation of the left hand side of the machine and showing certain details of the drive for the rollers;

2

Fig. 5 is a broken top plan view with one of the rollers removed;

Fig. 6 is a broken section taken on line 6—6 of Fig. 5;

Fig. 7 is a broken section taken on line 7—7 of Fig. 5;

Fig. 8 is a broken section taken on line 8—8 of Fig. 1;

Fig. 9 is a broken perspective view of the folding member.

The operative parts of the machine are mounted on or suspended from a top plate 10 which is supported on legs 11. Side frames 12 and 13 are mounted in spaced relation on the top plate. Shafts 14 and 15 which carry two lower rollers 16 and 17 are journaled for rotation above the top plate. Bearings 18 for shaft 14 are mounted on the side plates. An upper roller 22 is mounted on shaft 21 and the bearings for shafts 15 and 21 are mounted on the top plate. These shafts are disposed on fixed axes and a second upper roller 23 is mounted on shaft 24. This shaft is journaled in arms 25 and 26. The opposite ends of these arms are journaled in stub shafts 27 and 28 and roller 23 is thus swingable from an upper to a lowered position.

Only shafts 14 and 15 are driven, driving being effected by a drive chain 31 (Fig. 4) which engages sprockets 33 and 32 keyed to such shafts. The chain also engages an idler 34 on shaft 35 and drive sprocket 36 keyed to drive shaft 37 journaled in brackets 41.

Rollers 16, 17 and 22, which may be formed from rubber or other resilient material, are of cylindrical shape whereas roller 23 has spaced annular recesses 42.

The work 43 (Fig. 2) is supported on a platen 44, the front end of which is mounted by means of a bracket 45 carried on a fixed shaft 46 supported at its ends by brackets 47 secured to side frames 12 and 13.

The other end of the platen is supported by a post 51 mounted at its lower end in top plate 10.

For the purpose of locating the work at the front of the machine an angle bracket 52 is provided which is movable forwardly or rearwardly to an adjusted fixed position where it is secured by a screw 50. To swing arms 25 and 26 downwardly, stub shafts 27 and 28 are provided with gears 53 and 54, keyed thereto and these gears are engaged by toothed racks 55 and 56 mounted for sliding vertical movement in the frame. At their lower ends the racks are pivotally secured at 59 to one end of levers 60 and 61, the opposite ends of the levers being pivoted to the frame at 62. The arms and the racks are moved downwardly

by cams 63 and 64 keyed to shaft 66. A roller 67 on each arm engages the outer periphery of the cam.

Shaft 66 is journaled in bearings 10 and is driven by means of a sprocket 71 freely carried thereon and a drive chain 72 which engages an idler 73 and is driven by a sprocket 74 keyed to drive shaft 37. This drive shaft is rotated by a motor (not shown) which may have a chain drive leading to sprocket 69 keyed to shaft 37, and during operation of the machine rollers 16 and 17 rotate continuously. Rotation of shaft 66 is discontinuous, however, and for this purpose a one-revolution clutch assembly is interposed between constantly rotating sprocket 71, freely carried on shaft 66, and such shaft. This comprises a notched gear 75 which rotates conjointly with sprocket 71 and a dog 76 pivoted at 77 on disc 78 keyed to shaft 66. When projection 80 on dog 76 enters a notch in gear 75, sprocket 71 drives shaft 66 and cams 63 and 64 through one revolution, thus drawing racks 55 and 56 downwardly, and swinging arms 25 and 26, carrying front upper roller 23 down to operative position against the work, and then up again for the next cycle of operation.

The contour of cams 63 and 64 is such as to retain roller 23 in this downward position for a sufficient period to enable it to engage the work until its trailing edge has passed the forward rollers. Racks 55 and 56 are positively driven only downwardly and return movement is effected by springs 81 secured at one end to arms 25 and 26 and at the other to fixed brackets 82 carried by the frame. Thus, rollers 67 are fast against the outer peripheries of cams 63 and 64 at all times.

The manual control for the one-revolution clutch assembly will now be described. Dog 76 is urged at all times in the direction of notched gear 75 by spring 83. It is normally held out of such engagement by lever 84 centrally pivoted at 85. A spring 86 urges lever 84 in a counter-clockwise direction (Fig. 3).

A foot treadle 90 is keyed to shaft 91 journaled between legs 11, and a link 92 also keyed to such shaft is connected at 93 to lever 94 suitably mounted for vertical reciprocating movement. The latter is formed with a shoulder 97 which supports the front terminal of lever 84. The upper end of lever 94 is bevelled at 95 and is arranged to contact fixed diagonal surface 96. Thus, when the treadle is depressed lever 94 moves upwardly actuating lever 84 and freeing the clutch assembly for rotation. Simultaneously, the upper end of lever 94 travels in the direction of the operator, thus freeing lever 84 to return to the position of Fig. 3 so as to disengage the dog after its one-revolution travel. A stop 98 limits rotation of lever 84 due to action of spring 86 and when treadle 90 is released, either before or after the one revolution, spring 100 returns lever 94 to the position of Fig. 3.

A word about the work 43 is in order at this point. The cardboard wall 101 is usually square and is uppermost. The paper blank 102 forming the other wall of the envelope has a forward edge or flap 103 and opposed edges or flaps 104 on two sides. The fourth or trailing edge of blank 102 is coextensive with the adjoining edge of blank 101. Another machine has applied adhesive to flaps 103 and 104 and has formed three crease lines defining the flaps so that the flaps are generally upwardly disposed. Also upper blank 101 has been placed in proper register on lower

blank 102 and in this condition the work is placed on platen 44 with the trailing edges of the blanks engaging bracket 52.

Vertical guide plates 105—106 are mounted in adjusted, fixed positions a distance apart equal to the width of blank 101 plus the thickness of flaps 104. This positioning is important in order to get a tight fold around the edges of the upper blank. These guide plates are secured to laterally extending supporting plates 107 and adjustment is effected by loosening set screws 108.

The rear edge of the platen is shown at 109 and there is also provided a rearward extension 99 of the platen which is spaced therefrom so as to expose the upper periphery of forward rollers 16 which is on substantially the same plane as the platen. If desired platen sections 44 and 99 may be formed in one piece with a suitable transverse opening for the first lower roller. A fixed brush 110 mounted in a bracket 111 initially bends forward flap 103 downwardly. If there is any initial tendency for the forward sections of the blanks to rise, there are restrained by a plate 112 carried by the swingable roller assembly and which in its lowered position is just above the work 43.

The novel contour of the folding members 113 is amply shown in Figs. 8, 9 and 6. They are provided with curved descending surfaces 114, which initially bend opposed flaps 104 downwardly before they encounter the rollers, and with vertical walls 119 which provide a tight fold of the flap over the edge of the heavy blank. These members are mounted on plates 115 which are pivoted at 116 and they are urged inwardly by springs 117. Inward movement is limited by a set screw 120 which contacts a fixed stop 121. After the finished article passes the second rollers it passes down chute 122.

The manner of placing the superimposed blanks on the platen has already been described. Rollers 16 and 17 are continuously rotating. The foot treadle is now depressed and roller 23 descends to the position shown in broken lines in Fig. 2 which urges the work into contact with roller 16 which drives the work forwardly where flaps 103 contact brush 110, giving it its initial fold. At about the time the leading edge of the work contacts rollers 17 and 22 the side folding members 113 have begun their work of folding down flaps 104. Any slight deviation from straight opposed edges of the work causes the folding members to retract slightly although vertical wall 119 is always in firm contact with the edge. If continuous operation of the machine is desired, it is only necessary to tie down the foot treadle or the entire manual control may be eliminated and timing of the descent of the upper forward roller is arranged by varying the contour of cams 63 and 64.

While one form or embodiment of the invention has been shown and described herein for illustrative purposes, and the construction and arrangement incidental to one specific application thereof has been disclosed and discussed in detail, it is to be understood that the invention is limited neither to the mere details or relative arrangement of parts, nor to its specific embodiment shown herein, but that extensive deviations from the illustrated form or embodiment of the invention may be made without departing from the principles thereof.

I claim:

1. A combination lining and edge finishing machine for superimposed blanks, the lowermost of

which is provided with adhesive applied flaps along the front edge and two opposed longitudinal edges, such machine comprising a frame, a platen provided with work-locating guides mounted on the frame, plural sets of upper and lower rollers journaled in the frame and whose meeting peripheries are generally planar with the platen, brushing means for initial folding of the front flap, and side folding members for initial folding of the side flaps, each folding member being provided with a side wall which merges into a descending surface, spring means for urging the folding members toward the blanks, means for driving the lower rollers, upwardly swingable arms supporting the first upper roller to allow for positioning the blanks upon the platen, and rack-and-pinion means for moving the arms downwardly.

2. A combination lining and edge finishing machine for flat containers with upstanding flaps comprising a frame, plural sets of upper and lower rollers, a brush for folding the forward flap, a platen having an opening exposing the upper periphery of the first lower roller, opposed guide members for locating the blanks on the platen, and folding members for turning down the opposed flaps prior to introduction to the rollers, power means for driving the lower rollers, swingable arms supporting the first upper rollers to raise the latter as the work is placed on the platen, gears carried by said arms, vertically disposed racks engaging the gears, a cam shaft provided with cams for moving the racks downwardly and manually operated means for controlling intermittent operation of the cams.

3. A combination lining and edge finishing machine for superimposed rectangular blanks, the lowermost of which is provided with adhesive applied flaps along two opposed longitudinal edges and at least one additional edge, such machine comprising a frame, a platen provided with work-locating guides mounted on the frame, two upper and lower rollers journaled in the frame and whose meeting peripheries are generally planar with the platen, a fixed brush for imparting an

initial fold to the front flap, and side folding members for initial folding of the side flaps, each folding member being provided with a vertical side wall which merges into a descending surface, a plate pivoted at its rear end on the frame supporting each folding member, a spring for urging each plate toward the blank, a motor for driving the lower rollers, upwardly swingable arms supporting the first upper roller to allow for positioning the blanks upon the platen, and rack-and-pinion means for moving the arms downwardly.

4. A combination lining and edge finishing machine for a flat record container comprising a lower wall formed with upstanding flaps and an upper wall, said machine comprising a frame, two pairs of upper and lower rollers, a brush for folding the forward flap, a platen to receive the work and whose rear end is adjacent to and substantially plane with the upper periphery of the first lower roller, opposed guide members for locating the blanks on the platen, and folding members for turning down the opposed flaps prior to introduction to the rollers, each formed with vertical edges which press the side flaps against the upper blank, and diagonally descending surfaces which force the flaps downwardly against the upper blank, power means for driving the lower rollers, swingable arms supporting the first upper rollers to raise the latter as the work is placed on the platen, gears carried by said arms, toothed driving means engaging the gears, a cam shaft provided with cams for actuating the driving means and manually operated means for controlling intermittent operation of the cams.
